TONE-ARM MOUNTING

Willard J. Faulkner, Chicago, Ill., assignor to Oak
Mfg. Co., Chicago, Ill., a corporation of Illinois

Application September 14, 1949, Serial No. 115,615

4 Claims. (Cl. 274—1)

1

This invention relates to a tone-arm mounting and is particularly concerned with the tone-arm supporting portion of an automatic record changer. The construction embodying the present invention is of general application but is particularly adapted for use with the record changer disclosed and claimed in the copending application of Arthur C. Ten Cate, Serial No. 88,213 filed April 18, 1949.

The invention in general contemplates a structure whereby the tone-arm portion of an automatic record changer has a simple and effective hinge and spring mounting so that both horizontal and vertical adjustments of the tone-arm are easily possible. Furthermore, the structure embodying the present invention provides a shock-proof mounting whereby when the tone-arm is manually moved horizontally against any retaining means on the part of the changer, the tone-arm will yield without damage to the mechanism. A particularly desirable feature of the invention resides in the fact that the mounting permits tone-arm balance with respect to the horizontal pivots. Thus a small, light tone-arm having low inertia and low needle pressure may be attained. With a tone-arm embodying the invention, the weight of the transducer element provides the necessary needle pressure. Other advantages will occur to those skilled in the art.

In order that the invention may be understood, it will now be explained in connection with the drawings wherein Figure 1 is a top view partly in section of a changer embodying the new tone-arm construction. Figure 2 is a side detail of the tone-arm mounting. Figure 3 is an enlarged sectional side view of the mounting of the tone-arm. Figure 4 is a sectional view generally similar to Figure 3 but showing other parts in section. Figure 5 is a section on broken line 5—5 of Figure 4 with a portion of the tone-arm shown in dotted lines forced out of normal position. Figure 6 is a detail of the mounting removed from the tone-arm.

Referring first to Figure 1, motor board 10 preferably of pressed steel has circular well 11 in which is bolted at 13, drive motor 15. The motor has shaft 16 engaging large rubber covered wheel 17 rotating around axis 18. Concentric with wheel 17 is small rubber drive shaft 20 extending adjacent the depending skirt of turntable 30. This drive is conventional in the art.

Rotatably disposed on spindle 21 and above well 11 is gear 31. This gear may have secured thereto suitable means in a turret for supporting a stack of records centrally of the records and 55

2

feeding the same one at a time on to turntable 30. The precise means for supporting and feeding the records is not necessary to a proper understanding of the invention and is therefore not fully disclosed herein. However, an example of such means is disclosed and claimed in the Ten Cate application previously referred to. Other record-supporting means may be used as desired.

Gear 31 is adapted to cooperate with gear 40 10 rotatively secured at 41 and provided with a number of cam surfaces and slots. Inasmuch as the details of this gear construction relate to the record feeding and timing means, no further disclosure thereof will be made except as necessary 15 for a proper understanding of the tone-arm actuating and elevating means.

Pivotedly supported at 45 (Figure 1) in motor board 10 is sleeve 46. This sleeve is supported in bearing 47 carried by the motor board. Sleeve 46 20 is rotatably supported but is prevented from longitudinal movement, that is movement vertically, by any suitable means.

Sleeve 46 carries (Figure 4) at lower end 50 arm 51 having fingers 52 and 53 at the ends thereof for 25 cooperation with the automatic record feeding mechanism. It is understood that arm 51 cooperates with suitable means for moving the arm over a predetermined angular range and is adapted to control the movement of the tone-arm 30 in a conventional manner.

Sleeve 46 has its upper end rigidly clamped in a generally U-shaped fixture 55. Fixture 55 has portions 56 and 57 connected together by bight 58. Portions 56 and 57 are suitable apertured 35 and connected by slotted portion 60 extending around the length of the material along the bight. Bolt 62 is disposed in the bight portion and may be used for tightening the two split portions around the end of the sleeve. Portion 56 has 40 upstanding wing portions 63 and 64. Wing portions 63 and 64 have slotted arms 65 and 66 bent toward each other. These two wing portions also have suitable apertures 67 and 68 therethrough. Tail portions 69 and 70 of the wing portions are bent toward each other and have pivotally 45 mounted therebetween rocker 72. Rocker 72 has rear portion 73 extending directly over the aligned apertures of the fixture.

Disposed in slots 67 and 68 of the bent arms is 50 pivot pin 76 supported by springs 77 and 78. Springs 77 and 78 are anchored in apertures in wings 63 and 64 and slots 79 and 80 of the pivot pin. The pivot pin has portions extending beyond the slotted wing portions as shown. These two 55 springs may be replaced by one central spring.

The assembly of sleeve and mounting fixture is pivotally secured to tone-arm 82 in the following manner. One end of pivot pin 76 extends through aperture 83 in one side wall of the tone-arm. This aperture is just large enough to accommodate the end of pivot pin for proper rocking action. The other end of the pivot pin is secured in an aperture of pivot support plate 85 adjustably secured at slot 86 to the opposing side of the tone-arm. Slot 87 in the tone-arm side is provided for accommodating the free end of the pivot pin. It will be noticed that slots 86 and 87 are elongated to allow for some adjustment of pivot pin support plate 85. Preferably the two slots in the side of the tone arm are wide enough to allow for some vertical adjustment of the tone arm with respect to the pivot pin as well as lateral adjustment.

Rocker 72 has end 88 formed as a finger and cooperates with stop plate 90 bolted to the rear side wall of the tone-arm. Preferably, plate 90 is adjustably secured to the tone-arm as by elongated slots in the tone-arm side wall so that the stop plate may be disposed in a desired position prior to tightening the bolts. Stop plate 90 is heavy enough so that it acts as a counter-weight for the tone-arm proper. Thus the tone-arm may be balanced at pivot pin 76 for vertical play. Cartridge 92 shown in dotted outline at the free end of the tone-arm will then provide the needle pressure necessary for tracking.

Pin 95 vertically movable in sleeve 46 will elevate the tone-arm. Thus when pin 95 is raised by suitable means at the end of a record playing cycle, it moves rocker 72 against stop 90 and forces the tone-arm to raise. When pin 95 drops, the tone-arm drops. Actual tone-arm elevation is secured only by raising pin 95 beyond the point where finger 88 of rocker 72 engages stop 90. The adjustment of stop plate 90 on the tone-arm will control tone-arm elevation.

If desired, a spring may be disposed between end 97 of fixture 55 and aperture 98 in rocker 72. Such a spring will reduce the needle pressure.

When the tone-arm is forced away from a normal horizontal position, springs 77 and 78

permit yielding of the tone-arm. This is shown in dotted lines in Figure 5. Upon release of the tone-arm, springs 77 and 78 return the same to its normal position.

5 What is claimed is:

1. In a phonograph, a tone-arm mounting comprising a fixture having a pair of curved slotted arms, a pivot pin passing through said slots and extending on opposite sides of said fixture, at least one spring anchored to said fixture and pin for retaining said pin against said fixture at the ends of the slots, a sleeve clamped by said fixture, a rocker arm pivotally secured to said fixture and having one end at the sleeve axis, said rocker arm axis being parallel to the pin axis in a normal pin position with the rocker arm and pin axes being spaced on opposite sides of the sleeve axis and perpendicular thereto, a tone-arm, said tone-arm having journals for the pin ends, a stop carried by the tone-arm, and a second pin vertically slidable in said sleeve to engage said one end of the rocker arm, the other end of said rocker arm being adapted to engage the stop, said pin serving to move said rocker arm and elevate the tone-arm, said spring permitting horizontal deflection of said tone-arm from a normal position.

2. The structure according to claim 1 wherein in said tone-arm has one of said journals adjustable whereby the horizontal tone-arm position relative to the fixtures may be predetermined.

3. The structure according to claim 1 wherein in the step is secured to the tone-arm and remote from the pick-up end and wherein said stop is adjustably secured to said tone-arm whereby the tone-arm elevation may be controlled.

4. The structure according to claim 1 wherein in said tone-arm has one pin journal adjustable and wherein said stop is adjustably carried so that horizontal and vertical tone-arm control is obtained.

WILLARD J. FAULKNER.
